(57) CLAIM

The ornamental design for a coat collar, as shown and described.

DESCRIPTION

FIG. 1 is a top left perspective view of a coat collar, and further depicting a collar in an upward position;

FIG. 2 is a top right perspective view of the coat collar shown in FIG. 1;

FIG. 3 is a top plan view of the coat collar shown in FIG. 1;

FIG. 4 is a front elevational view of the coat collar shown in FIG. 1;

FIG. 5 is a left side elevational view of the coat collar shown in FIG. 1;

FIG. 6 is a rear elevational view of the coat collar shown in FIG. 1;

FIG. 7 is a right side elevational view of the coat collar shown in FIG. 1;

FIG. 8 is a front perspective view of the coat collar shown in FIG. 1, and further depicting the collar in a downward position;

FIG. 9 is a top plan view of the coat collar shown in FIG. 8;

FIG. 10 is a front elevational view of the coat collar shown in FIG. 8;

FIG. 11 is a left side elevational view of the coat collar shown in FIG. 8;

FIG. 12 is a rear elevational view of the coat collar shown in FIG. 8;

FIG. 13 is a right side elevational view of the coat collar shown in FIG. 8; and,

FIG. 14 is a bottom plan view of the coat collar shown in FIGS. 1-13, and further depicting the coat collar flattened for purpose of illustrating the design.

The broken lines depicted in the drawings represent stitching and form part of the claimed design.
